UNITED STATES PATENT OFFICE.

JOSEPH DERK, OF DOYLESTOWN, PENNSYLVANIA, ASSIGNOR TO THE DERK MANUFACTURING COMPANY, OF DOYLESTOWN, PENNSYLVANIA, A CORPORATION OF PENNSYLVANIA.

DESIGN FOR A TABLE SCARF.

Application filed June 28, 1928. Serial No. 27,300. Term of patent 3½ years.

To all whom it may concern:

Be it known that I, JOSEPH DERK, a citizen of the United States, residing at Doylestown, in the county of Bucks, State of Pennsylvania, have invented a new, original, and ornamental Design for a Table Scarf, of which the following is a specification, reference being had to the accompanying drawing, forming part thereof.

The figure is a plan view of a table scarf showing my new design. The design illustrated constitutes practically one-half of the table scarf, and the design is repeated at the opposite end.

I claim:

The ornamental design for a table scarf, as shown and described.

JOSEPH DERK.
